(57) **CLAIM**

The ornamental design for a bracket for an emergency shutoff drive, as shown and described.

DESCRIPTION

FIG. 1 is a rear perspective view of a bracket for an emergency shutoff drive;

FIG. 2 is a right side plan view of the bracket for an emergency shutoff drive;

FIG. 3 is a front plan view of the bracket for an emergency shutoff drive;

FIG. 4 is a rear perspective view of the bracket for an emergency shutoff drive;

FIG. 5 is a front perspective view of the bracket for an emergency shutoff drive;

FIG. 6 is a front perspective view of the bracket for an emergency shutoff drive;

FIG. 7 is a front plan view of the bracket for an emergency shutoff drive;

FIG. 8 is a top plan view of the bracket for an emergency shutoff drive;

FIG. 9 is a bottom plan view of the bracket for an emergency shutoff drive;

FIG. 10 is a right side plan view of the bracket for an emergency shutoff drive; and,

FIG. 11 is a left side plan view of the bracket for an emergency shutoff drive.

The broken lines shown in the figures are for the purpose of illustrating portions of the bracket, an electric drive, a valve, and a gas cylinder which form no part of the claimed design. No claim is made regarding the position or relative size of the design with respect to the electric drive, valve, or gas cylinder.
